UNITED STATES PATENT OFFICE.

JOHN E. SMID, OF GEORGE, IOWA.

WRITING-TABLET.

1,093,082.

Specification of Letters Patent. Patented Apr. 14, 1914.

Application filed July 10, 1913. Serial No. 778,345.

To all whom it may concern:

Be it known that I, JOHN E. SMID, a citizen of the United States, residing at George, in the county of Lyon and State of Iowa, have invented certain new and useful Improvements in Writing-Tablets; and I do hereby declare the following to be a full, clear, and exact description of the invention, such as will enable others skilled in the art to which it appertains to make and use the same.

This invention comprehends improvements in writing tablets and relates more particularly to those of the continuous type wherein a strip of paper is unwound from one spool and wound upon another.

The primary object of the invention resides in the provision of a writing or figuring tablet of this nature which will be of use by cashiers, paying tellers, and bookkeepers, but which may also be found useful by persons employed in other ways who may have occasion to do considerable figuring.

Another object of the invention is to provide a device of this nature which will hold the exposed portion of the paper practically on a level with the supporting surface which may be a desk, table, or counter, and which may be easily operated so as to feed the paper, whereby a fresh surface is exposed for writing or figuring.

Another and more specific object of the invention is to provide a novel form of brake or stop device for the rolls of paper.

With these and other objects in view, as will become more apparent as the description proceeds, the invention consists in certain novel features of construction, combination, and arrangement of parts, as will be hereinafter described and claimed.

For a complete understanding of my invention, reference is to be had to the following description and accompanying drawings, in which,

Figure 1 is a top plan view of my device, showing the same attached to a supporting surface, Fig. 2 is a side elevation with the supporting surface shown in section, Fig. 3 is a bottom plan view of the device, Fig. 4 is a transverse section, parts of the machine being shown in elevation; and, Fig. 5 is a detail side elevation of one of the brake or tension plates.

Referring in detail to the drawings by numerals, 1 designates a suitable support, such as a desk, table, or counter, which in

the present instance is cut away to form a rectangular opening 2 for the accommodation of my improved writing or figuring tablet. A base plate 3 is positioned over the opening 2 and is somewhat larger than the opening, extending beyond the side edges of the same over the top of the supporting surface. The end portions of the plate are bent downwardly into the opening, as indicated by the numeral 4, and form bearing surfaces for the paper, to be described later. Depending lugs 5 are formed adjacent the corners of the base plate for reception within openings formed in the supporting surface so as to hold the plate in its proper position. The plate is also formed adjacent one end with paper guides 6, which engage the edges of the paper strip, as it is moving over the plate.

A pair of U-shaped frames, generally designated 7 and 8 and having the depending arms 9, are secured to the under side of the base plate 3, for the purpose of supporting the spools 10 and 11. The spool 10 revolves freely about the shaft 12, whereas the spool 11 is fixed to and movable with the shaft 13. This last mentioned shaft has rigidly secured to one end a bevel gear 14, which meshes with a similar gear 15 secured to the lower end of a vertical shaft 16. The shaft 16 extends through a bearing 17 secured to one of the arms 9 of the frame 8 and also through an opening formed in the base plate 3. A crank handle 18 is secured to the upper end of the shaft 16 so that the latter may be easily rotated so as to wind the paper 19 from the spool 10 onto the spool 11. As is clearly shown in the drawings, the paper passes from the spool 10 over the upper surface of the base plate, between the guides 6, and down under the base plate to the spool 11.

In order to prevent the spools rotating too rapidly, I provide the tension or brake plates 20. These plates are preferably formed of sheet metal and have their lower extremities enlarged and curved toward each other, as indicated by the numeral 21. A pair of sleeves 22 is formed upon the upper edge of one of the plates and a sleeve 23 is formed upon the upper edge of the other plate, for reception within the sleeves 22. A pintle or pivot rod 24 extends through the sleeves and is secured at its ends within the ears 25 formed on the under side of the plate 3. A curved rod 26 having enlargements 27

formed upon its extremities, extends through openings formed in the plates 20 and the expansive spiral spring 28 surrounds that portion of said rod which extends between the plates. The spring forces the plates against the paper rolled upon the spools 10 and 11 and as one paper roll increases in size while the other diminishes, the plates swing about the pintle 24 as a pivot. To place the machine in proper running order the spool 10 carrying a full roll of paper is placed in the frame 7, and one end of the paper carried over the outer surface of the base plate and attached to the spool 11. Then as the exposed surface of the paper is covered with figures or writing the shaft 16 is rotated so as to cause the paper to wind upon the spool 11, whereby a fresh surface is exposed. When the paper is entirely wound upon the spool 11, the shaft 16 is raised so as to carry the gear 15 above the gear 14 and then after the cotter pin 29 has been removed the shaft 13 may be withdrawn from the frame 8 in order to detach the spool 11. After this has been done, the empty spool 10 is transferred to the position primarily occupied by the spool 11 and a fresh roll of paper placed in the frame 7. If it is desired to review some of the figures or writing upon the paper strip, said strip may be grasped and pulled backwardly so as to unwind the paper from the spool 11.

From the foregoing description taken in connection with the accompanying drawings, it will be apparent that I have provided an extremely simple figuring or writing tablet which may be conveniently secured to a suitable surface so as not to be in the way, and which may be very easily operated so as to wind paper from one roll to another, whereby a clean writing surface is continuously exposed.

It is to be understood that while I have

shown and described the preferred embodiment of my invention, I do not wish to be limited to this exact construction, combination, and arrangement of parts, but may make such changes as will fall within the spirit and scope of the invention as claimed.

Having thus described my invention, I claim:

1. In a device of the character described, a base plate, a pair of paper rolls, means for winding the paper from one roll to the other, and a brake comprising a pair of brake plates pivotally secured at their upper ends to the base plate and projecting between the paper rolls, a curved rod extending through openings formed in the plates and having its center of curvature at the pivot point of the brake plates, and an expansive spiral spring surrounding that portion of the rod included between the plates, whereby said plates are forced against the rolls.

2. The combination with a supporting surface having an opening formed therein, of a base plate positioned over said opening and resting upon the supporting surface, said base plate being formed with depending lugs engaging with the supporting surface, spools supported under said plate, means for winding paper from one spool to the other, the paper passing over the top of the plate, a pair of ears formed upon the under side of the plate between the spools, a pivoted rod supported by said ears, a pair of brake plates connected to said pivot rod, and means for forcing the plates against the spools.

In testimony whereof I affix my signature in presence of two witnesses.

JOHN E. SMID.
